(57) **CLAIM**

I claim the ornamental design for a medical and dental apparatus, as shown and described.

DESCRIPTION

FIG. 1 is an isometric view of a medical and dental apparatus with the upper instrument holding means thereof in the retracted position.

FIG. 2 is a front view of the medical and dental apparatus with the upper instrument holding means thereof in the retracted position.

FIG. 3 is a top view of the medical and dental apparatus with the upper instrument holding means thereof in the retracted position.

FIG. 4 is a right side view of the medical and dental apparatus with the upper instrument holding means thereof in the retracted position.

FIG. 5 is a left side view of the medical and dental apparatus with the upper instrument holding means thereof in the retracted position.

FIG. 6 is a rear view of the medical and dental apparatus with the upper instrument holding means thereof in the retracted position.

FIG. 7 is an isometric view of the medical and dental apparatus with the upper instrument holding means thereof in an extended position.

FIG. 8 is a front view of the medical and dental apparatus with the upper instrument holding means thereof in the extended position.

FIG. 9 is a top view of the medical and dental apparatus with the upper instrument holding means thereof in the extended position.

FIG. 10 is a right side view of the medical and dental apparatus with the upper instrument holding means thereof in the extended position.

FIG. 11 is a left side view of the medical and dental apparatus with the upper instrument holding means thereof in the extended position; and,

FIG. 12 is a rear view of the medical and dental apparatus with the upper instrument holding means thereof in the extended position.
